RATCHET SCREWDRIVER

Barney J. Enrietto, 920 La Farge, Louisville, Colo.

Filed Oct. 7, 1965, Ser. No. 87,359

Term of patent 14 years

(Cl. D93—4)

FIG. 1.

FIG. 2.

FIG. 3.

FIG. 4.

FIGURE 1 is a top plan view of the ratchet screwdriver showing my new design;

FIGURE 2 is a front elevational view thereof;

FIGURE 3 is a left end view thereof; and

FIGURE 4 is a right end view thereof.

I claim:

The ornamental design for the ratchet screwdriver, as shown.
